Attorney.

UNITED STATES PATENT OFFICE.

CHARLES A. BAILEY, OF CROMWELL, CONNECTICUT.

CARTRIDGE.

SPECIFICATION forming part of Letters Patent No. 694,713, dated March 4, 1902.

Application filed October 22, 1901. Serial No. 79,536. (No model.)

To all whom it may concern:

Be it known that I, CHARLES A. BAILEY, a citizen of the United States, and a resident of Cromwell, in the county of Middlesex and State of Connecticut, have invented certain new and useful Improvements in Cartridges, of which the following is a specification.

The object of my invention is to provide a simple, cheap, and effective means for firmly and securely connecting the parts of a paper-tube cartridge together and in such manner that there will be no possible chance of the tube becoming separated from the cap or head in abstracting the cartridge from the firearm, 15 the breech construction of the cartridge being such that the part which holds the tube in place will also serve as a reinforce.

With the above objects in view my invention consists, broadly, in a cartridge comprising a flanged cap or head, a tube inserted therein, and a breech-piece having spurs or projections which are embedded in the tube, the said breech-piece being forced into the flange of the cap or head.

25 My invention further consists in the particular construction and combination of the parts, all as will be hereinafter fully described, and more specifically set forth in the appended claims.

30 In the accompanying drawings, which form a part of this specification, Figure 1 is a longitudinal sectional view of a cartridge constructed in accordance with my invention. Fig. 2 is a similar view illustrating the operation of connecting the parts. Fig. 3 is a longitudinal sectional view illustrating a modified form of breech-piece. Fig. 4 is a detail view of the breech-piece.

In carrying out my invention the cartridge-40 shell is made up of three parts—to wit, the head or cap A, the tube B, and the breech-piece C—and these parts are intimately and firmly connected together to form a strong and durable cartridge.

45 The head or cap A is provided with the usual flange a, which is formed by expanding the rim to provide an annular recess a' within said flange and into which the ends of the tube and breech-piece are forced, as hereinafter 50 described. The end of the head or cap may be solid, as shown in Figs. 1 and 2, to form a gas-tight cartridge, or it may be provided with

an inwardly-projecting open-ended nipple (see Fig. 3) to receive an ordinary primer, and I purpose to use either form of primer 55 with both the preferred construction of cartridge (illustrated in Figs. 1, 2, and 4) and that employing the modified form of breech-piece, as illustrated in Fig. 3.

The tube B, which may be either entirely 60 of paper or composed of several thicknesses of paper and metal, is crimped inward at its inner end, forming the flange b. This tube is adapted to fit the cap or head snugly, and when it is inserted the crimped end bears 65 against the end of said cap or head, as shown in Fig. 2.

The breech-piece C is dished or cup shape, being struck up from a disk of metal, and the edge of this breech-piece is cut away at intervals to form a series of spurs or points c, which are adapted to be embedded in the tube and enter the annular recess formed by the flange a of the cap or head. The central portion of the breech-piece is bulged, as shown 75 at c', and the fulminate is placed upon the inner side of this bulged portion, forming a gas-tight cartridge in connection with a solid head. The bulged portion is indented, forming a central internal point c'', to insure the 80 explosion of the fulminate, and at each side of said point are flash-holes c'', which communicate with the powder charge. When the breech-piece is employed in connection with an ordinary primer, the central portion is provided with an opening, so that said breech-piece 85 will fit over the nipple.

In connecting the parts hereinbefore described they are assembled as shown in Fig. 2, and by inserting a punch the breech-piece 90 is flattened out, forcing the spurs or points into the paper tube at the corner thereof, and said points or spurs enter the annular recess a' of the flange a of the cap or head, being wedged therein to firmly and securely hold 95 the parts together. By forcing only a portion of the periphery of the breech-piece into the tube the end of latter is not liable to be cut off, as would be likely to occur should the periphery be provided with a straight edge. By 100 this construction of cartridge the paper tube is securely fastened to the cap or head and the parts are not liable to become separated. It will also be noted that the breech-piece re-

inforces the cap or head, forming a thicker wall at the breech of the cartridge. The cartridge is simple in construction and can be manufactured at small expense, using comparatively thin metal.

To provide for further reinforcing the breech of the cartridge, I purpose to use a breech-piece as illustrated in Fig. 3, in which said breech-piece (designated by the letter *e*) is formed with a sleeve having spurs *e'*, the end wall *e²* being flattened into the flange *f*, forming the flange *e³*. This cap or head is provided with a nipple *f'* to receive an ordinary primer, and the end wall of the breech-piece is provided with a central opening, through which said nipple projects. With this form of cartridge a straight tube is used, and when the punch is inserted the flange *e³* of the breech-piece enters the flange *f* of the head or cap, and the spurs *e'* enter the tube to hold it securely in engagement with said breech-piece. I contemplate providing the breech-piece with a spiral rib instead of the spurs.

Having thus particularly described my invention, I do not wish to be understood as limiting my protection by patent to what is herein particularly shown and described, for it is obvious that changes could be made in the construction and arrangement of parts without departing from the spirit of my invention.

I claim—

1. A cartridge, comprising a flanged cap or head, a tube inserted therein, and a breech-piece having a portion of its periphery embedded into the tube and projected into the flange of the cap or head, substantially as shown and described.
2. A cartridge, comprising a flanged cap or head, a tube inserted therein, and a breech-

piece having spurs or points embedded in the tube and aforesaid flange of the cap or head, substantially as shown and described.

3. In a cartridge, the combination with the 45 cap or head having a flange forming an annular recess, of the tube crimped inward at its inner end, and a cup-shaped disk bulged centrally and having a portion of its periphery embedded in the crimped end of the tube 50 and projected into the aforesaid recess of the cap or head, substantially as shown and described.

4. In a cartridge, the combination, of the 55 cap or head having a flange forming an annular recess, a tube having a crimped end inserted in the cap or head, and a cup-shaped disk having points at its edge which are forced into the tube and recess, substantially as shown and described.

60 5. In a cartridge, the combination, of a cap or head having a flange forming an annular recess, a tube having a crimped end inserted in the cap or head, and a cup-shaped disk bulged centrally and provided at its edge with 65 spurs or points which are forced into the tube and aforesaid recess, substantially as shown and described.

6. In a cartridge, the combination, of a cap or head having a flange forming an annular 70 recess, a tube having a crimped end inserted into the cap or head, and a cup-shaped disk cut away at its edge to form points or spurs which are forced into the tube and aforesaid recess, substantially as shown and described. 75

In testimony whereof I affix my signature in the presence of two witnesses.

CHAS. A. BAILEY.
